UNITED STATES PATENT OFFICE.

RUDOLPH W. GLASNER, OF CHICAGO, ILLINOIS.

INTERLACING-MACHINE.

1,389,043,

Specification of Letters Patent. Patented Aug. 30, 1921.

Application filed April 28, 1919. Serial No. 293,346.

To all whom it may concern:

Be it known that I, RUDOLPH W. GLASNER, a citizen of the United States, residing at Chicago, in the county of Cook and State of Illinois, have invented certain new and useful Improvements in Interlacing-Machines, of which the following is a specification.

This invention relates to improvements in interlacing machines for fibrous material, particularly adapted, though not necessarily limited in its use, for curled horse hair.

Heretofore with machines of this character considerable difficulty and inconvenience has been experienced in feeding the material to the needles in that the bat of material will be of uneven thickness, that is to say the bat will contain thin spots which are not always visible while the material is being fed, resulting in an uneven pad after the interlacing operation.

To overcome these difficulties and objections and to provide improved means embodying a transparent support across which the material is fed and having illuminating means such as lights arranged beneath the support and visible therethrough, so as to expose the weak or thin portions of the bat, to enable the operator to fill in the thin spots during the feeding operation, is one of the objects of the present invention.

A further object is to provide an improved machine of this character having means for uniformly feeding the entire supply of material to the needles and embodying means for preventing the forward portion of the supply from being disintegrated or separated from the supply, with the result that a more rapid production and greater output will be obtained, and also rendering it possible to finish a complete pad in one operation, which pad will be of a uniform thickness.

A further object is to provide an improved machine of this character embodying a plurality of needles connected with an adjustably mounted support, and which support and needles are adapted to be readily detached or removed from the machine without dismantling the remaining parts and while the material is in the machine. This will render it possible to replace at any stage of the operation of the machine any one or more of the needles which may become damaged or broken without removing the material from the machine.

A further object is to provide an improved

machine of this character having means for feeding a sheet of backing material to the needle and to which backing the fibrous material is secured by the interlacing operation, the backing serving as a support upon which the fibrous material is carried to the needle, and improved means for maintaining the backing material against twisting or wrinkling during the feeding operation thereof.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which:

Figure 1 is a view in elevation as taken from the right hand side of a machine of this character constructed in accordance with the principles of this invention.

Fig. 2 is a vertical sectional view as taken on line 2—2, Fig. 1.

Fig. 3 is a horizontal sectional view taken on line 3—3, Fig. 4.

Fig. 4 is a detail view in elevation of the left hand side of the machine.

Fig. 5 is a detail vertical sectional view taken on line 5—5, Fig. 2.

Fig. 6 is a view partly in vertical section and partly in elevation of a needle bar, needle and support.

Fig. 7 is a horizontal sectional view taken on line 7—7, Fig. 6.

Fig. 8 is a top plan view of the machine.

Fig. 9 is a detail sectional view taken on line 9—9, Fig. 8.

Fig. 10 is a diagrammatic view in elevation of a modified form of the invention.

Fig. 11 is a view similar to Fig. 2 of a modified form of the invention.

Fig. 12 is a detail view showing the operating pawl.

Figs. 13 and 14 are cross-sections taken on Fig. 11, lines 13—13 and 14—14, respectively.

Referring more particularly to the drawings, the machine consists primarily of spaced supports 15 of any desired size and configuration and mounted upon the supports are uprights 16 which carry a superstructure embodying a frame having side members 17 and a connecting member 18 extending across the top of the members 17. Additional supports 19 are provided which

are spaced from the support 15 and the supports 15 and 19 are connected by side members 20, all combined to construct a frame of any desired size. The side bars or members 20 constitute a portion of the support to receive the material that is being fed and which support comprises a transparent table 21 which may be constructed of any suitable transparent material, such as glass, of a size 10 to extend over the entire support or may be constructed of sections as shown more clearly in Fig. 8 and which sections are separated and supported by cross members 22 arranged between the side members 20. The 15 support thus formed may be of any desired length.

Arranged at the forward end of the machine and adjacent the support 21 is a feed roller 23 journaled in suitable bearings with 20 its axis below the support and with its periphery substantially flush with the top of the support 21 so as to assist in feeding the material across the support. At the rear of the support is another feed roller 24 which 25 coöperates with the feed roller 23 to feed the material and arranged beneath the support are lamps 25 suitably spaced and so arranged that they will be visible through the transparent support. With this arrangement it 30 will be manifest that as the material 26 is being fed across the support the light from the lamps 25 will be visible through the thin portions of the bat of the material, thereby enabling the operator to fill in the thin 35 spaces in the bat before they reach the interlacing needles. This will insure a bat of uniform thickness.

At the forward end of the support and in 40 proximity to the feeding roll 23, and journaled in bearings 17^a mounted in openings 17^b in the side members 17 of the frame and in a position to receive the material from the support are rollers between which the material passes. These rollers are preferably 45 constructed of a plurality of laterally spaced disks 27, 28 secured respectively to shafts 29, 30 to rotate with the shafts. The shafts 29, 30 are preferably arranged out of alignment, that is with the diametric centers 50 of the shafts displaced laterally with respect to each other for a purpose to be hereinafter set forth, and the peripheries of the disks 27, 28 together with the peripheries of the feed rolls 23—24 are preferably roughened 55 or knurled so as to insure a gripping of the material by the rolls and disks and prevent relative slipping and at the same time also prevent the material from adhering to the rolls.

60 The bearings 17^a are adjustable in the openings 17^b by adjusting devices 17^c such as screws, and clamping screws 17^d may be provided for holding the bearings in their adjusted positions.

65 Arranged also at the front of the ma-

chine and in advance of the disks 27, 28 and journaled in the side members 17 of the frame are additional feed rolls 31—32 spaced so that the material 26 will pass therebetween and these rolls assist in feeding the 70 material through the machine. Adjustable bearings 31^a movable in opening 31^b are provided for the roll 31, and are adjustable by the adjusting screws 31^c, and may be secured in their adjusted positions by the screws 31^d. 75

Motion may be imparted to the rolls and disks in any suitable manner but preferably in the following manner. Brackets 33 are provided which are adapted to reciprocate upon the uprights or standards 16, and these 80 brackets are connected for simultaneous reciprocation by means of a connecting bar 34 which constitutes a support for the needles, to be hereinafter described. Journaled in the frame 15 is a shaft 35 which extends 85 thereacross and this shaft is given a rotary motion in any desired or suitable manner and is provided with a fly wheel 36. Secured to the shaft 35 at any convenient points are spaced eccentrics 37 with which 90 eccentrics straps 38 coöperate and these straps are connected by means of the bars 29 with the support 34 so that as the shaft 35 is rotated the support 34 and brackets 33 will be given a reciprocatory movement 95 upon the standards 16. Connected with the shaft 30 on the left hand side of the machine and outside of the frame is a gear wheel 40 and a similar gear wheel 41 is connected with the feed roller 32, an intermediate gear 42 being provided between the gears 40 and 41 to cause the feed roll 32 and disks 28 to rotate in unison and in the same direction. A ratchet gear 43 is connected with the gear 42 to rotate therewith and a pawl 44 is provided for operating the ratchet gear 43. This is accomplished by mounting the pawl 44 upon an upright 45 and which upright is adjustably mounted in one of the brackets 33, a spring being provided for 100 maintaining the pawl 44 in operative position with respect to the ratchet 43 so that when the bracket 33 is reciprocated it will be manifest that during the upward movement thereof the pawl 44 will ride over the teeth of the ratchet 43, but when the bracket 33 is moving in the opposite or downward direction the pawl will engage the teeth of the ratchet to rotate the disks 28 and the feed roll 32. A similar mechanism is provided for operating the upper series of disks 110 27 and feed roll 31 but the operating mechanism therefor is preferably arranged on the opposite side of the machine and embodies gears 46—47 connected respectively to rotate with the disks 27 and feed roll 31, with an intermediate gear 48 between the gears 46—47. A ratchet gear 49 is connected to the gear 48 to rotate therewith and a pawl 50 is connected with a reciprocat- 115

120

125

130

ing support 51 for operating the ratchet gear 49, and the support 51 is adjustably mounted in one of the brackets 33. The gear 48 and ratchet 49 are preferably mounted upon a support or plate 49^a connected to move with the adjustable bearings 17^a and 31^a. The pawl 50 is controlled by a spring 52 similar to the spring which controls the pawl 44. By thus adjustably mounting the supports 45—51 it will be manifest that the extent of movement of the rolls under the operation of the pawls may be varied.

This extent of movement may also be varied in another manner such as by providing an extension 53 on the pawl which extends to the opposite side of the pivot and coöperating with this extension is an adjustable stop device 54 for limiting the movement of the pawl in one direction. Thus it will be seen that when the stop 54 is adjusted, the movement of the pawl about its pivot will be controlled or limited by the engagement of the extension with the stop.

The interlacing operation is accomplished by means of interlacing needles 55, the bill 56 of the needle being deflected laterally beyond the plane of the body of the needle so as to insure the engagement with the fiber. The needle is mounted or detachably secured to a needle bar 57 preferably so as to be detached therefrom and to that end the needle bar is provided with a recess 58 opening through one end and which recess is eccentrically mounted, that is, to one side of the diametric center of the end of the needle bar and into which recess the end of the needle is inserted and is held in position by means of a fastening device 59 such as a screw, the end of which is adapted to enter a recess 60 in the needle so as to correctly position the needle with respect to the needle bar. These needles are all secured to the support 34 so as to be detached therefrom and to that end the support 34 is provided with a series of recesses 61 opening through the top thereof, and the needle bar is provided with a recess 62 in one face adapted to receive the end of a fastening device or screw 63. With this construction of needle and needle bar it will be manifest that by the provision of the recesses 60 and 62 together with the fastening devices 59—63 coöperating therewith, it will be impossible to place the needle and needle bar in the machine in an incorrect position and will always insure the proper positioning of the needle.

As before stated the support 34 is detachably connected with the brackets 33. This may be accomplished in any suitable manner but preferably by means of fastening devices 64 such as screws which pass through suitable slots 65 in the support 34 and engage the respective brackets 33. Thus it will be manifest that inasmuch as the

support 34 with the needles and needle bars connected therewith are detachably secured in position, and as the support 34 together with the fastening devices 64 are always accessible, the whole support 34 with the needles may be readily detached and removed from the machine to permit the repair or insertion or removal of the needles without dismantling any of the other part of the mechanism even while the material is in the machine and at any time during the interlacing operation.

In order that the support 34 may be readily replaced in proper position after being once removed so as to obviate the necessity of any further adjustment, there may be provided guides for positioning the support, such for instance, as adjustable stops 66 in the form of screws which are located at a point to be readily accessible.

Motion may be imparted to the feed rolls 23—24 in any suitable manner but preferably from the disks 28 by means of a beveled gear 67 secured to the shaft 30 and preferably on the outside of the frame. Meshing with this beveled gear 67 is another gear 68 carried by a shaft 69 mounted in suitable bearings 70 and which shaft extends along one side of the machine. Connected with the shaft 69 to rotate therewith is a beveled gear 71 meshing with a beveled gear 72 to rotate with the feed roll 23. Another beveled gear 73 is connected with the shaft 69 and meshes with the beveled gear 74 connected with the feed roll 24. Thus, when the disks 28 are rotated a simultaneous and uniform rotation will be imparted to the feed rolls 23—24.

Mounted upon the supporting structure in a convenient position and so as to hold a roll of backing material 75 beneath the frame and out of the way, are suitable brackets 76. The backing material 75 is fed from the roll, over the feed roll 24, across the support 21, and through the interlacing mechanism. This backing may be constructed of any suitable flexible material and is provided in the event that it is desired to secure a pad to a backing. When employed, the backing forms a support upon which the material 26 is placed and carried forward. In order to insure the proper feeding of the backing, an additional roller 77 is provided at the rear of the machine and adjacent the roll 24. The periphery of this roller 77 may also be roughened or knurled and is of a length substantially equal to the length of the roll 24 and between which rolls 24 and 77, the backing material passes. The roll 77 is mounted eccentrically in bearings 78 and connected with which bearings is a yoke 79 which operates as a handle to move the roll 77 bodily away from the roll 24 when the yoke 79 is in an upright position as shown in dotted lines in Fig. 1 but when

the yoke is in the full line position shown in Fig. 1, the roll 77 will be moved toward the roll 24 to grip the backing 75 and the weight of the yoke is sufficient to hold the roller 77 under tension with respect to the backing to insure a gripping operation.

This roll 77 is given its motion from the shaft 69 through the medium of a beveled gear 80 on the shaft which meshes with the 10 beveled gear 81 connected with the roll 77. When the roll 77 is moved into an inoperative relation with respect to the roll 24, that is when the yoke 79 is in the dotted line position of Fig. 1 the beveled gear 81 will 15 be moved out of operative relation with the beveled gear 80.

With this improved construction it will be manifest that the material will be given a uniform feeding movement and this will increase 20 the rapidity of the output and when the backing is employed, the provision of the roll 77 serves the further function of maintaining the backing even or straight and against a wrinkling or twisting movement 25 during the feeding thereof.

When it is desired to dispense with the backing, an endless flexible belt 82^a may be employed (see Fig. 10) and when so employed the belt will pass over the rolls 30 23—24. The belt is preferably constructed of a fabric and it is of course understood that the belt is of such a texture that it will be transparent to such an extent that the lights will be visible therethrough.

It will also be manifest that by the provision 35 of the roll 24, which co-operates with the roll 23, the material will be fed uniformly and will be given a feeding movement throughout substantially the entire 40 area of the material being fed. This is particularly advantageous because the material may be fed across the support 21 without the use of the backing 75 or the belt 82^a, and in that event the material will be given 45 its feeding movement by the rolls in the interlacing portion of the machine with which co-operate the rolls 23—24, thereby obviating the danger of disintegrating or separating the forward portion of the material from 50 the remaining portion as would be the case if the material was advanced solely by the rolls adjacent the needles. By applying a feeding movement or a power at the rear of the supply, it will be manifest that this separation 55 will be obviated and the material will be advanced uniformly over the support.

In the event that it is desired to construct the pads of different widths, there may be 60 provided a guide 81 (shown in Fig. 10) which is adapted to be placed upon the support 20 and extends lengthwise of the support. By the provision of the adjustable bearings 17^a and 31^a, it will be manifest that 65 the disk rolls 27 and the feed roll 31 may

be adjusted respectively with relation to the disk rolls 28 and feed roll 32 to vary the thickness of the pad, and in order that the ratchet mechanism of the upper rolls may be maintained in operative relation during 70 such adjustment, a supporting plate 49^a is provided which is connected for adjustment with the bearings.

In the event that it is desired to construct a machine of this character for manufacturing pads of considerable width, it is necessary 75 to increase the width of the machine and this will in turn increase the length of the shafts upon which the disks 27 and 28 are connected, with the result that there 80 might be a tendency of the shafts to have a springing action. In order therefore to maintain these shafts against such action, suitable braces may be provided such as a support 82 which is adjustably connected by 85 means of screw threads 83 to a transverse bar or support 84, which in turn is connected with the main supporting structure 15 and located below the needle bar support 34. A fastening nut 85 may be provided for holding 90 the support 82 in position. This support 82 is threaded into the support 84 and is preferably provided with a yoke 86 at the top thereof having a pivoted or swivel connection with the support 82 at 87 to allow 95 the yoke 86 to assume a proper position with respect to the shaft 28^a and permit the adjustment of the support 82. Thus the shaft 28^a upon which the disks 28 are mounted 100 will have a bearing in the yoke and will be braced against springing action. A somewhat similar brace may be provided for the shaft 27^a to which the disks 27 are secured. This latter brace comprises a yoke 88 having 105 a threaded stem 89, the latter being threaded in a bracket 90 secured to the cross bar 18 and a fastening nut 91 may be provided if desired upon the threaded end of the stem 89. The yoke 88 is swiveled to the stem 89 in the same manner that the yoke 86 is 110 swiveled to the brace 82.

It will thus be seen that these braces will hold the shafts in proper position and against a springing action.

By offsetting the shafts 29—30 of the disks 115 27—28 laterally with respect to each other, it is possible to arrange the needles 55 and needle bars 57 so as to operate in close proximity to the shaft 30 and between the disks 28. This arrangement will also permit the 120 arrangement of the needles 55 so that the points thereof will be in substantially a direct line with the axis of the shaft 29, so that the disks 27 will form a rest against which the material engages during the interlacing operation and prevent the pad from becoming distorted.

While the preferred form of the invention has been herein shown and described, it is to be understood that various changes may 130

be made in the details of construction and in the combination and arrangement of the several parts within the scope of the claims, without departing from the spirit of this invention.

What is claimed as new is:—

1. An interlacing machine embodying a reciprocatory needle, means for imparting such movement to the needle, and means for feeding the material across the path of reciprocation of the needle, the last recited means embodying a stationary transparent support for the material extending for a considerable distance from the needle, illuminating means beneath the support for directing light rays therethrough, and provisions for automatically and uniformly feeding the material throughout substantially the entire length of the said support. 15
2. An interlacing machine embodying a reciprocatory needle, means for imparting such movement to the needle, and means for feeding the material across the path of reciprocation of the needle, the last recited means embodying a stationary transparent support along which the material is fed, illuminating means beneath the support for directing light rays therethrough, a feeding element adjacent the needle and at one end 25 of the support, and additional feeding means spaced from the last recited means and in a direction lengthwise of the support, whereby the entire supply of material upon the support will be fed thereacross 30 and to the first recited feeding element. 35
3. A needle bar for interlacing machines embodying a body portion, a needle connected to and extending from one end thereof, said body being provided with a recess 40 adjacent the other end and opening through the side of the body, a support having a recess to receive the recessed end of the said body, said support having an opening extending through one face thereof transverse 45 to the recess and communicating with the recess, and a fastening device passing through the said opening and extending into the recess in the end of the said body portion of the needle bar for alining and 50 positioning the needle. 55
4. An interlacing machine embodying interlacing mechanism, a transparent support adjacent and projecting beyond the interlacing mechanism and over which support the bat of material is fed to said mechanism, illuminating means disposed beneath such support for directing rays of light therethrough, means for advancing the material over the support, and means 60 cooperating with the support and adjustable with respect thereto in a direction transverse to the direction of feeding movement of the material to vary the width of bat to be supplied to the interlacing mechanism. 65
5. A needle bar for interlacing machines embodying a body portion provided with a recess opening through one end and arranged to one side of the diametric center of said end, a needle proper adapted to be seated in said recess, and coöperating means on the needle bar and needle for properly positioning the needle with respect to the needle bar when the needle is seated in said recess. 75
6. A needle bar for interlacing machines embodying a body portion provided with a recess opening through one end and arranged to one side of the diametric center of said end, a needle proper adapted to be seated in said recess, coöperating means on the needle bar and needle for properly positioning the needle with respect to the needle bar when the needle is seated in said recess, a support for the needle bar, said support having a recess to receive the end of the needle bar, and coöperating means on the support and needle bar for properly positioning the needle when the needle bar is connected with the said support. 80
7. An interlacing machine embodying interlacing mechanism, a support adjacent and projecting beyond the interlacing mechanism and over which support the bat of material is fed to said mechanism, means for advancing the material over the support, and an adjustable guide device extending lengthwise of the support and adjustable with respect to the support in a direction transverse to the direction of feeding movement of the material to vary the width of the bat to be supplied to the interlacing mechanism. 95
8. An interlacing machine embodying interlacing mechanism, a support adjacent and projecting beyond the interlacing mechanism and over which support the bat of material is fed to said mechanism, means for advancing the material over the support, and an adjustable guide device extending lengthwise of the support and adjustable with respect to the support in a direction transverse to the direction of feeding movement of the material to vary the width of the bat to be supplied to the interlacing mechanism, and whereby a plurality of pads may be simultaneously formed by the said interlacing mechanism. 100
9. An interlacing machine embodying spaced parallel shafts, laterally spaced co-operating disks on the shafts and between which disks the material passes, a supporting structure for the shafts and disks, needles operating in the spaces between the disks, and a brace arranged intermediate the ends of each of the shafts and disposed between the supporting structure and the respective shafts for bracing the latter. 110
10. An interlacing machine embodying spaced parallel shafts, laterally spaced co- 115
- 120
- 125
- 130

operating disks in the shafts and between which disks the material passes, a supporting structure for the shafts and disks, needles operating in the spaces between the disks, and a brace arranged intermediate the ends of each of the shafts and disposed between the supporting structure and the respective shafts for bracing the latter, each of said braces having a bearing at its end in which the shaft rotates.

10 11. An interlacing machine embodying spaced parallel shafts, laterally spaced co-operating disks in the shafts and between

which disks the material passes, a supporting structure for the shafts and disks, needles operating in the spaces between the disks, a brace arranged intermediate the ends of each of the shafts and disposed between the supporting structure and the respective shafts for bracing the latter, and 15 means for adjusting said braces.

20 In testimony whereof I have signed my name to this specification, on this 26th day of April, A. D. 1919.

RUDLOPH W. GLASNER.
